Primary Examiner — Brett Miller

(57) **CLAIM**

The ornamental design for a cutting machine, as shown and described.

DESCRIPTION

FIG. 1 is a first perspective view of a cutting machine showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the cutting machine thereof.

The broken lines shown in the drawings depict portions of the cutting machine in which the design is embodied that form no part of the claimed design.

1 Claim, 9 Drawing Sheets
